Term of patent 14 years

(Cl. D26—5)

Fig. 3

Fig. 4

FIGURE 1 is a perspective view of an electrical control cabinet section embodying my new design;

FIG. 2 is a fragmentary cross-sectional view taken on line 2—2 of FIG. 1;

FIG. 3 is a perspective view of a modified form of the control center section shown in FIGURE 1; and

FIG. 4 is an enlarged front elevational view of one of the control panels.

The dominant features of my new design reside in the portions shown in full lines.

I claim:

The ornamental design for an electrical control cabinet, substantially as shown and described.
